[57] CLAIM

The ornamental design for an insect electrocuter, as shown and described.

DESCRIPTION

FIG. 1 is a perspective view of an insect electrocuter in accordance with my new design;

FIG. 2 is a top plan view thereof;

FIG. 3 is a side elevational view thereof; and

FIG. 4 is a bottom plan view thereof.

The pole shown in broken lines in FIG. 1, is disclosed for illustrative purposes only.

FIG. 1

FIG. 2

FIG. 3

FIG. 4
